(57) **CLAIM**

The ornamental design for a connector for a ratchet screwdriver, as shown and described.

DESCRIPTION

FIG. 1 is a perspective view of a connector for a ratchet screwdriver, showing my new design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof;

FIG. 7 is a bottom plan view thereof; and,

FIG. 8 is a perspective operational view thereof for reference showing a replaceable shank attached to the connector and the connector attached to a handle.

The broken line portions of the disclosure are for illustrative purposes only and form no part of the claimed design.
